TABLE

William Owen Goodwin, Chicago, Ill.

Application June 4, 1934, Serial No. 728,900

7 Claims. (Cl. 38—105)

The invention, in general, relates to improvements in a table, but more particularly to that type of table ordinarily termed a kitchen table, and in this instance, in particular, the invention 5 contemplates in combination with a table which provides the feature of a dining table, an extendible ironing board, a so-called bread board, a rolling pin, and the provision of space for the reception of an electric flat iron, and a water 10 sprinkler, and of the ironing board, the bread board, and the rolling pin.

The invention further contemplates a table having the above characteristics having oppositely folding leaves whereby the top area of the 15 table may be increased from its normal size, and having, what may be termed, a disappearing ironing board installed therewith which may be withdrawn from within the table frame or sides and be rigidly supported and locked against one 20 of the side edges of the table top so that, during the operation of ironing, the board or ironing table can not swing laterally or become loosened from its extended horizontal position.

The invention further contemplates a table 25 having the above characteristics which requires but the usual space required for an ordinary kitchen table.

A further important object of the invention 30 contemplates the installation of the several items above mentioned in a table of the above type whereby the conservation of space, time and labor, may be obtained, as well as the saving of many steps of the housewife or the person in whose place such devices may be installed.

35 The invention further contemplates a device having the above characteristics which provides compactness, simplicity of operation and of construction, and which may be manufactured at, comparatively, a very small cost, and which provides a table of neat design notwithstanding the addition thereto of the items above mentioned. The invention also provides the installation of an electric device to which the iron may be connected and to which connection may be made to the 40 source of electrical supply.

45 These and other objects of the invention may be better understood from the several illustrations in the accompanying drawings, and from the description as more fully described in the following specification, and more particularly pointed out in the appended claims.

In the several illustrations,

Figure 1 is a perspective view of the invention 50 as seen from the end from which the ironing board may be withdrawn.

Figure 2 is a perspective view of the invention with a position of the near table leaf broken away, showing the position or place of installation of the bread board and the rolling pin.

Figure 3 is a plan view of the invention, with 5 the top and leaves of the table removed and showing, in general, the position of the ironing board, the bread board, the rolling pin, the flat iron, and the water sprinkler, as is installed within the sides or frame of the table, and the electrical 10 device to which electrical connections may be made to the electric iron and the source of electric supply.

Figure 4 is a sectional view taken on the plane 4—4, of Figure 3, showing top and leaf in place.

Figure 5 is a sectional view taken on the plane 15 5—5, of Figures 3 and 4, showing top and leaves in place.

Figure 6 is a sectional view as seen from the plane 4—4, of Figure 3, but showing the ironing 20 board withdrawn and installed in its extended position as when being used in performing ironing operations, and showing top and leaf in place.

Figure 7 is a plan view of Figure 6.

Figure 8 is an enlarged detail sectional view 25 showing a method of fastening closure in its normal closed position.

In the illustrations similar characters refer to 30 similar parts throughout.

This invention contemplates an ironing board 35 10, a bread board 11, a rolling pin 12, and, in this instance, a type of table 13, commonly known as a kitchen table, in combination with each other. The table, in this instance, is, however, provided with oppositely folding leaves 13', which provides 40 means for enlarging the top area of the table should it be required. The table has the usual top 14, sides or frame 15, and legs 16. In one side of the frame 15, as side 17, an opening 18 is provided through which a tube 19, is inserted and there fastened in any suitable manner in the position shown. The tube provides a receptacle for 45 the rolling pin 12. In another side of frame 15, as side 20, is provided an elongated opening or slot 21, through which the bread board 11, may be inserted. The board 11 is supported by guide rails 22, and is fastened in any suitable manner to opposite side frames 20, and 23. In side frame 15, as side 24, is provided an opening 25, which is 50 closed by a hinged closure 26, the purpose of which will be explained later, and, as well, the means for holding the same in its closed upright position. In the side 24, is suitably fastened double wall-sockets 27, to which electric connection 55 may be made to an electric iron 28, and to the

source of electrical supply being located at some convenient place in the room in which my invention may be installed. Extending across from sides 20 to 23, and back from side 24, is provided a shelf or plate 29, having an upstanding portion 30, which provides a place for the reception and support for the iron 28, and a water sprinkler, 31. The plate 29, being fastened in any suitable manner to the side frames 20, 23, and 24.

10 As previously mentioned, the ironing board 10, may be termed a disappearing ironing board for the reason that it may be returned from its outwardly extended usable position to its unusable or unseen position within the side frames 15, and 15 under the top 14, of the table 13. In this case, the padding, and such like, is not being shown on the ironing board.

The general construction, scheme, and installation of an ironing board to a table, and the position to which it is placed when being used in performing ironing operations, will be clearly understood by referring to, particularly, Figures 3, 4, 5, 6, and 7. In this instance, in order to support the board 10, in its outwardly extended position, 25 as is shown in Figures 6 and 7, the board is provided on its one end, as at end 10', and on the underside thereof, outstanding lugs 32, which prevent the board from being pried up when a weight or force is being applied upon the top of the board 30 beyond the brace or strut 33, which is hingedly fastened to the underside of the board, as by a hinge 34, placed a suitable distance out from the end 10'. The remaining portion 10'', of the board, beyond hinge 34, is further supported against a 35 hinged brace 35, and is hingedly secured at its lower end to brace 35, as by a hinge 36, the other or upper end thereof being supported against a stop 37, which is secured by any suitable means to the underside of board 10. In order to further 40 support the board in its extended position, as is shown in Figures 6 and 7, and to prevent the board from being moved or swung laterally from the position shown in Figure 7, an adjustable locking and limit stop mechanism is provided consisting of several parts or members included in which are, 45 in this instance, two pairs of identical telescoping members comprising, in each pair, a permanently positioned rod 38, over which is telescoped a tube 39. The bar or rod 38, is secured through a suitable loop or staple 40, provided in a plate 41, which is securely fastened by any suitable means to the inside of side-frame 17, the bar 38, being suitably formed at its end 38', in a manner such that the same can not be withdrawn from its fastening 50 or loop 40. Over the free end of bar 38, is fastened, as, for instance, by means of sweating together, a short piece of tubing 42, which is adapted to freely slide through the tube 39. Over the end of the tube 39, as at 39', is threaded a screw-cap 43, having a central opening 44, through which rod 38, is adapted to loosely fit. The tubing 42 and cap 43 provide means for limiting the outward movement of tube 39 when the board 10 is being withdrawn to its 55 usable or extended position shown in Figures 6 and 7. The tube 39, being threaded, as at 39'', to receive an adjusting or limiting nut 45, is inserted through a suitable opening 46, provided in an angle-bar 47, which is suitably positioned and 60 fastened by any suitable means, as by screws 48, to the underside of the end 10', of the board 10.

When the board 10, is in its retracted position within the side frames 15, of the table, as is shown in Figures 3 and 4, the closure 26, is normally held 75 in its closed position by means of, as for instance,

a spring actuated button catch 49. On desiring to withdraw the board 10, for use, the closure 26, is swung open on its hinges 50. The board 10, being withdrawn to its extended position, as particularly shown in Figure 6, causes the telescoping mechanism to be in its extended position, which, being in the proper adjustment, prevents the board 10, from being withdrawn further than is shown in Figures 6 and 7, that being, to a point where the end of the board and the edge of the 10 table coincide with one another, as at 51. In order to bring the board up to the position shown in Figure 6, and so that the stops or lugs 32, are snugly against the underside of the top of the table, the closure 26, is swung back to its normal position, or so that the bottom of the notches 52, provided in the closure, and which match with the tubes 39, press tightly against the tubes 39.

When it is desired to return the board 10, to its 20 normal or unseen position, it becomes only necessary to open the closure 26, release brace 35 from stop 37, and pull out on the brace 33, the board will then drop below the top of the table sufficiently so that the board and the telescoping mechanism may be pushed back to its, as before mentioned, normal or out-of-the-way position within the side-frames 15, of the table 13. A longitudinal central support 53, being provided upon which the ironing board is being supported 25 when the same is in its retracted position.

Having thus described my invention it can be readily understood that the minor details of its construction may be altered in several ways without departing from the spirit and scope of the invention, and without losing any of its attendant advantages. Therefore, what is claimed 30 is desired to be secured by Letters Patent.

I claim:

1. A table of the character described, having a 40 box-like side frame and a horizontally retractible ironing board installed within said frame, said frame and board being connected to each other by an adjustable telescoping mechanism, an opening in one of the sides of said frame through which to withdraw said board, a hinged closure for closing said opening, said telescoping mechanism and said closure being adapted to rigidly support said board in its withdrawn position against one of the side edges of the top of the table, and hinged means for supporting the board in its usable position on being withdrawn. 45

2. A table of the character described, having a 50 box-like side frame and a horizontally retractible ironing board installed within said frame immediately beneath the top of the table, adjustable telescoping mechanism connecting said frame and board together, an opening in one of the sides of said frame through which the said board may be withdrawn, means for rigidly supporting the board in its usable withdrawn position against one of the side edges of the top of the table, said telescoping mechanism adapted to limit the distance to which the board may be withdrawn, and means to adjust the limit of outward travel of said telescoping mechanism. 55

3. A table of the character described, having a 60 box-like side frame and a horizontally retractible ironing board installed within said frame immediately beneath the top of the table, an opening in one of the sides of said frame through which said board may be withdrawn, a hinged closure for said opening and for supporting the said board in its usable withdrawn position, adjustable telescoping mechanism with which to attach said board and frame together and for 65

70

75

limiting the distance to which the said board may be withdrawn from within the said frame, the said closure providing means by which to raise and rigidly support the board in its usable withdrawn position level with the top of the table, and means for rigidly supporting the ironing board in its withdrawn position against one of the side edges of the top of the table.

4. A table of the character described, having a box-like side frame and a horizontally retractible ironing board installed within the said frame immediately beneath the top of the table, adjustable telescoping mechanism with which to attach said board and table to one another, an opening in the side frame through which the ironing board may be moved, a hinged closure for said opening, said mechanism being adapted to limit the distance to which the said board may be withdrawn from within the table, and said closure together with hinged braces providing means for rigidly supporting the ironing board in its usable position against one of the side edges of the top of the table.

5. A table of the character described, having a box-like side frame and a horizontally retractible ironing board installed within the said frame immediately beneath the top of the table, adjustable telescoping mechanism with which to attach said board and table to one another, an opening in the said frame through which to operate said board, a hinged closure for said opening, said mechanism being adapted to limit the outward and inward travel of the said board, means for adjusting the limit of movement of said mechanism, the said closure being adapted

to rigidly support the said board in its outwardly withdrawn position level with the top of the table and the said board and telescoping mechanism against lateral movement, and hinged members being so arranged and adapted to firmly support the board in a horizontal usable position.

6. A table of the character described, having a box-like side frame and a horizontally retractible ironing board associated therewith, adjustable telescoping mechanism providing connection between said board and table, an opening provided in one of the sides of said frame through which the said board may be moved, a hinged closure for closing said opening and for supporting the board in its outwardly withdrawn position, and means upon which to support said board and telescoping mechanism in a retracted position within said frame.

7. An ironing board retractibly secured to and within the sides of a box-like frame of a table, adjustable telescoping mechanism for connecting said board with one of the sides of said frame, means by which to adjust and limit the movement of said mechanism, a closable opening provided in said frame through which said board and mechanism may move, a hinged closure for closing said opening and for supporting said mechanism and the board on being withdrawn from within said frame, and a suitable arrangement of hinged members and said mechanism being adapted to rigidly support said board in its usable position and against any lateral or downward force.
